TOY VEHICLE

Cecil P. Caulkins, New London, Conn.

Application May 15, 1935, Serial No. 21,585

5 Claims. (Cl. 280—87.5)

This invention relates to improvements in toy vehicles, and especially to a novel construction of parts which are so constructed and arranged that they may be interchanged to vary the character 5 of the device to increase its utility and attractiveness.

The object of the invention is to provide a vehicle of novel construction which has a special appeal to children because of its variety of uses. 10 This will appear in the following specification in which the construction and interchangeability of the parts and the various objects of the invention will be described and its novel features pointed out in appended claims.

15 Referring to the drawing,

Fig. 1 is a side elevation of a toy cart which embodies my invention;

Fig. 2 is a plan view of the parts shown in Fig. 1 with the position of an extra seat indicated 20 by broken lines;

Fig. 3 is a side elevation of some of the parts shown in Fig. 1 assembled in a different way; and

Fig. 4 is a side elevation of some of the parts shown in the preceding figures used as a mounting 25 for a toy cannon.

Like characters of reference designate corresponding parts on each of the figures.

The vehicle comprises a pair of divergent side frames 10 fastened together near their front end 30 by a transverse bar 11, near the rear by a transverse bar 12 and by an intermediate transverse bar 13. 14 and 15 designate spaced slots in the upper surface of the side frames which are provided for a purpose which will appear later. The 35 parts of the side frames which extend rearwardly from the transverse bar 12 are shaped to form handles 16. The parts of the side frames which extend forwardly from the transverse bar 11 are beveled to form parallel faces 17. 18 is an axle affixed to the transverse bar 12 with wheels 19 40 on it.

20 is a yoke, the lower rear end of which fits between the parallel faces 17 and is removably secured to the side frames by bolts and wing nuts 45 21. 22 and 23 are the members of a butt which are hinged together by a loose pin 24. The butt member 22 is permanently affixed to the front edge of the yoke 20.

The other butt member 23 is permanently 50 affixed to a post 30 on the lower end of which are spacing blocks 31. 32 is an axle which runs through the post 30 and the blocks 31 to support wheels 33 which are nearer together than are the wheels 19. The axle 32 extends transversely 55 beyond the outside of the wheels 33 to receive

and support foot rests 34. These too are removable. 35 are holes in post 30 so positioned that they may be placed to align with the bolts which secure the yoke 20 to the side frames.

Handle bars 36, 36 are pivotally connected with the upper end of the post 30 by a pin 37. 38 5 is a handle at the other end of the handle bars and affixed to them in such a way as to hold them in spaced parallel relation. This arrangement is such that when the handle bars are in 10 the position in which they are shown in Fig. 2 or that indicated by broken lines at 36A in Fig. 1, they overlie the yoke 20 and lock the post 30 from turning.

40 is a seat which is arranged to be removably 15 secured to the vehicle frame by a through bolt 41 which passes through the transverse bar 11, and a wing nut 42. 43 (broken lines in Fig. 2) is a similar seat which is adapted to be removably secured to the frame by a through bolt 44 20 which passes through the transverse bar 13, and a wing nut 45.

A removable body is provided. This comprises a base 50, in the central axis of which are two 25 holes 51 and 52, sides 53, 53 which may be removed if desired, and a front 54. Under the forward end of the base 50 is a transverse batten 55 adapted to fit into the slots 14 or 15.

60 (Fig. 4) is an elongated member, circular in cross section, shaped to simulate a gun or 30 cannon. Near its rear end is a socket 61 adapted to fit the butt member 23 and to receive the pin 24. 62 are lugs attached to the barrel 60 to engage the sides of post 30 to prevent rotation.

Now, having pointed out the various parts of 35 this device, I will describe how it is used.

First, referring to the parts assembled as shown in Figs. 1 and 2, a cart or wagon is formed having a low center of gravity, with a driver's seat and a receptacle body. In this case, the batten 55 40 is in slots 15 and bolt 44 through hole 51. With the handle bars locked in the manner previously described, this will run along a straight path. Or, if the child seated on the seat 40, desires to 45 steer it, this can be done by raising the handle bars above yoke 20 into the position in which they are shown in full lines in Fig. 1, or above such position. The steering may be done by the handle 38 or by the foot rests 34 or by both. If the cart is to be drawn, the handle bars are 50 moved over post 30 into some such position as that in which they are shown in Fig. 3, or indicated by broken lines at 36B in Fig. 1. It is obvious that the device, as illustrated in Figs. 1 and 2, may be used also as a coaster and that 55

it can be used either with or without the body sides 53.

Second, by removing the body the device may be used as a coaster or as a scooter. When the body is off the second seat 43 may be attached to provide for two children to ride seated on the vehicle whether it is used as a coaster, drawn as a cart or propelled in some other way.

Third, by removing the seats 40, 43 the body 10 can be moved forwardly on the frame and attached thereto with its batten 55 seated in grooves 14 and the bolt 44 through hole 52.

Fourth, by removing the yoke 20 from the frame and affixing the post 30 in its place, first 15 removing pin 24 to disconnect the post from the yoke, the wheelbarrow effect illustrated in Fig. 3 is obtained. This may be raised by the handles 16 and drawn by the handle 38, or the latter may be disconnected and removed. 20 The relative positions of the wheels give this device considerable stability.

Fifth, the cannon-like member 60 may be connected with the post 30 by means of the pin 24 to produce the cannon and gun carriage effect 25 illustrated in Fig. 4.

By means of the parts herein shown and described, a toy is provided which is capable of many variations and uses, which fascinate children and prolong their interest and amusement. 30 The construction and arrangement of the parts may be varied considerably without departing from the spirit and scope of my invention and I intend no limitations other than those imposed by the appended claims.

35 What I claim is:

1. A toy vehicle having an assembled wheeled structure comprising diverging side frames and a plurality of transverse bars permanently affixed thereto, an axle affixed to one of the cross bars 40 intermediate the length of said side frames near the more widely separated ends thereof and a pair of wheels on said axle, the ends of the side frames which extend to the rear of the axle being shaped to form handles, the other end of the 45 side frames having parallel surfaces permanently held in spaced relation by said cross bars, combined with a wheel supporting device having flat sides shaped to fit between said parallel surfaces and adapted to be removably fastened to the side members, a front axle across the lower end of 50 said device and a pair of wheels on said front axle on either side of said device.

2. A toy vehicle having an assembled wheeled structure comprising diverging side frames and 55 a plurality of transverse bars permanently affixed thereto, an axle affixed to one of the cross bars intermediate the length of said side frames near the more widely separated ends thereof and a pair of wheels on said axle, the ends of the side 60 frames which extend to the rear of the axle being shaped to form handles, the other end of the side frames having parallel surfaces permanently held in spaced relation by said cross bars, combined with a wheel supporting device having flat 65 sides shaped to fit between said parallel surfaces and adapted to be removably fastened to the side members, a front axle across the lower end of said device, a pair of wheels on said front axle on either side of said device, and a pair of spaced handle bars horizontally pivoted to the upper part of said device and adapted to engage the sides thereof.

3. A toy vehicle having an assembled wheeled

structure comprising diverging side frames and a plurality of transverse bars permanently affixed thereto, an axle affixed to one of the cross bars intermediate the length of said side frames near the more widely separated ends thereof and a pair of wheels on said axle, the ends of the side frames which extend to the rear of the axle being shaped to form handles, the other end of the side frames having parallel surfaces permanently held in spaced relation by said cross bars, combined with a wheel supporting device having flat sides shaped to fit between said parallel surfaces and adapted to be removably fastened to the side members, a front axle across the lower end of said device, a pair of wheels on said front axle on either side of said device, a body having a part adapted to fit into the side frames in different longitudinal positions thereon, and means for fastening the body to a transverse bar in each of the different longitudinal positions of the body 20 on the side frames.

4. A toy vehicle having an assembled wheeled structure comprising diverging side frames and a plurality of transverse bars permanently affixed thereto, an axle affixed to one of the cross bars 25 intermediate the length of said side frames near the more widely separated ends thereof and a pair of wheels on said axle, the ends of the side frames which extend to the rear of the axle being shaped to form handles, the other end of the side frames having parallel surfaces permanently held in spaced relation by said cross bars, combined with a wheel supporting device having flat sides shaped to fit between said parallel surfaces and adapted to be removably fastened to the side members, a front axle across the lower end of 30 said device, a pair of wheels on said front axle on either side of said device, a seat adapted to be supported on the side frames in different longitudinal positions thereon, and means for fastening the seat to a transverse bar in each of the different longitudinal positions of the seat on the side frames.

5. A toy vehicle having an assembled wheeled structure comprising diverging side frames and a plurality of transverse bars permanently affixed thereto, an axle affixed to one of the cross bars intermediate the length of said side frames near the more widely separated ends thereof and a pair of wheels on said axle, the ends of the side frames which extend to the rear of the axle being shaped to form handles, the other end of the side frames having parallel surfaces permanently held in spaced relation by said cross bars, combined with a wheel supporting device having flat sides shaped to fit between said parallel surfaces and adapted to be removably fastened to the side members, a front axle across the lower end of said device, a pair of wheels on said front axle on either side of said device, a pair of spaced handle bars horizontally pivoted to the upper part of said device and adapted to engage the sides thereof, a body having a part adapted to fit into the side frames in different longitudinal positions thereon, means for fastening the body to a transverse bar in each of the different longitudinal positions of the body on the side frames, a seat adapted to be supported on the side frames in different longitudinal positions thereon, and means for fastening the seat to a transverse bar in each of the different longitudinal positions of the seat on the side frames.

CECIL P. CAULKINS.
